ROTARY LAWN MOWER

Henry L. Heineke, Springfield, Ill.

Application November 3, 1955, Serial No. 38,715

Term of patent 14 years

(Cl. D40—1)

Fig. 1.

Fig. 2.

FIG. 3.

FIG. 4.

FIG. 5.

FIG. 6.

Fig. 1 is a top plan view of a rotary lawn mower embodying my new design;

Fig. 2 is a side elevation of the right side thereof;

Fig. 3 is a side elevation of the left side thereof;

Fig. 4 is a bottom plan thereof;

Fig. 5 is a front elevation thereof; and

Fig. 6 is a rear elevation thereof.

The essential features of the design reside in the portions shown in full lines. The handle of the lawn mower illustrated in broken lines is shown broken away for convenience of illustration.

I claim:

The ornamental design for a rotary lawn mower, substantially as shown and described.
